UNITED STATES PATENT OFFICE.

JOHN T. STOREY, OF PHILADELPHIA, PENNSYLVANIA.

DESIGN FOR A BATTERY-PLATE.

SPECIFICATION forming part of Design No. 32,160, dated January 30, 1900.

Application filed December 29, 1899. Serial No. 742,002. Term of patent 14 years.

To all whom it may concern:

Be it known that I, JOHN T. STOREY, a citizen of the United States, residing in the city and county of Philadelphia, State of Pennsylvania, have invented and produced a new and original Design for Battery-Plates, of which the following is a specification, reference being had to the accompanying drawings, forming part thereof.

10 The leading features of my design for a battery-plate are, first, a plate composed of a frame and a coil of ribbon therein; next, fields at the corners of the frame on the interior thereof, and finally a bar extending over said coil.

15 Figure 1 represents a face view of a battery-plate embodying my design. Fig. 2 represents a horizontal section on line xx , Fig. 1.

In the drawings, A designates a frame, with-
in which is the coiled ribbon B.

20 C designates fields on the inner corners of the frame, and D designates bars on opposite sides of the plate extending over said ribbon B from the adjacent portions of the frame A.

Having thus described my invention, what I claim as new, and desire to secure by Letters Patent, is—

25 The design for a battery-plate substantially as shown and described.

JOHN T. STOREY.
